UNITED STATES PATENT OFFICE.

PERCY J. CALLOWHILL, OF PROVIDENCE, RHODE ISLAND.

VANITY CASE.

Application filed February 9, 1925. Serial No. 8,064.

To all whom it may concern:

Be it known that I, PERCY J. CALLOWHILL, a citizen of the United States, residing at Providence, in the county of Providence and 5 State of Rhode Island, have invented new and useful Improvements in Vanity Cases, of which the following is a specification.

This invention relates to certain new and useful improvements in vanity cases and the 10 primary object thereof is to provide a novel type of vanity case, equipped with a carrying cord having a lip stick holder forming a handle or finger grip at its free end.

A further object of the invention is to provide 15 means for removably mounting a perfume vial on the case and to also provide novel decorative means for concealing the vial carrier, which means permits the carrier to be easily and quickly moved into and out 20 of its several positions.

The invention has still further and other objects which will be later herein set forth and of themselves manifested in the course 25 of the following description.

25 In the drawings:—

Figure 1 is a side elevation partly broken away to show the vial carrier;

Figure 2 is a similar view showing the parts in open position and showing the concealing means complete, but in fragment;

Figure 3 is a section on line 3—3 of Fig. 2;

Figure 4 is a section on line 4—4 of Fig. 3

Figure 5 is a detail view of the catch

Figure 6 is a section on line 6—6 of Fig. 1

35 Figure 7 is a side elevation of the lip stick carrier, and

Figure 8 is an enlarged fragmentary view of the vial carrier, partly broken away.

In proceeding in accordance with the present 40 invention, a case is employed having a body 1, a double faced mirror 2 and a cover 3, the mirror and cover being hinged to the body for relative independent movement by means of a common hinge 4. The cover 3 is formed to receive a cake of rouge, while the body 1 is formed to receive powder. A spring arm 5 has upper and lower catches 6 and 7 on its free end and a thumb piece 8 in order to latch the cover to the mirror and 45 the mirror to the body whereby upon lateral movement of the arm same will release either the cover to expose the rouge or the mirror to expose the powder, or both as shown in the position of the parts depicted in Figure 50 2 of the drawings.

An eye 9 is secured to the cover and has one end of a carrying cord 10 attached thereto, the opposite end of the cord being attached to an eye 11 on the center of a cylindrical lip-stick holder 12. The lip stick is 60 mounted in a tubular carrier member 13 longitudinally slotted at 14, and through which slot the shank of a push button 15 slides, the shank of the push button being connected to a cup 16 slidable in the member 13. The cup 65 16 is formed to receive the inner end of a lip stick 17 and is restricted in its outward movement by a stop 18 secured in the member 13.

The member 13 is removably held within 70 the holder 12 by friction.

The body 1 is provided with an eye 19 to which is connected a carrier or case 20 for a vial of perfume P. The case 20 has a removable top 21 connected thereto by means 75 of a bayonet-slot and pin connection 22. Fringe 23 is secured to the body 1 and depends therefrom forming a tassel which completely conceals the case 20.

From the foregoing it will be seen that the 80 lip stick holder affords a convenient carrying handle for the entire structure, and at the same time the carrier member 13, with the lip stick therein, may be removed from the holder and projected, by means of the 85 push button 15.

Movement of the latch arm 5 releases both the cover from the mirror and the latter from the body, while the perfume case may be readily swung as desired through the fringe, 90 and its top then removed to permit removal of the perfume vial. The fringe forms a tassel in effect, but also conceals the vial case and at the same time permits same to be readily moved into and out of normal or 95 concealed position.

Having thus described my invention, what I claim as new and desire to secure by Letters Patent is:—

1. In combination with a vanity case, a 100 carrying cord connected at one end to the case, a tubular lip-stick holder connected to the opposite end of the cord, a lip-stick carrier frictionally held in the holder, said holder forming a carrying handle, a vial carrier 105 suspended from the case, and fringe suspended from the case in surrounding relation to the vial carrier to conceal same and to permit the carrier to be moved through the fringe to expose same. 110

2. In combination with a vanity case, a carrying cord connected at one end to the case, a tubular lipstick holder connected to the opposite end of the cord and a lip-stick carrier frictionally held in the holder.
3. In combination with a vanity case, a carrying cord connected to the case, a lipstick holder connected to the cord and constituting a carrying handle, and a lip stick carried by the holder.
4. In combination with a vanity case, a vial carrier, means to suspend the carrier from beneath the bottom of the case, a fringe disposed in encircling relation to and about the carrier and its suspending means so as to normally conceal each, and means to attach the fringe about the periphery of the case so that the latter provides a head for the fringe.
5. In combination with a vanity case, a carrying member connected to the case, a lip stick holder connected to the carrying member and constituting a handle, said holder having a closed and an open end, and a lip stick carrier removably engaged in the holder and movable into and out of the latter through said open end thereof.
6. In combination with a vanity case, fringe connected to the peripheral part of said case in encircling relation thereto and depending therefrom, means to connect the fringe to the case, a vanity carrier, and other means whereby to movably connect the carrier to the case so as to cause the carrier to be concealed by the fringe and to allow movement of the carrier through the fringe so as to permit access to the carrier.
7. In combination with a vanity case a vial carrier swingingly suspended from the case, a fringe suspended from the case in surrounding relation to the carrier to conceal same and permit of movement of the carrier through the fringe to gain access thereto, a flexible member connected to the case, and a lip stick holder connected to the flexible member.
8. In combination with a vanity case, a carrying member connected thereto, a handle forming element connected to the carrying member, and a vanity article carried by the handle.
9. In combination with a vanity case, a carrying member connected thereto, a handle forming element of tubular form connected centrally of its length to the carrying member, and a vanity article removably housed within the handle forming element.

In testimony whereof I have signed my name to this specification.

PERCY J. CALLOWHILL.
